Fig. 1.

Fig. 4.

Fig. 3.

Fig. 2.

Fig.5.

Fig.6.

Fig.7.

FIG. 1 is a front perspective view of a cooking range embodying the new design, with the surface heating unit in retracted position;

FIG. 2 is a front elevational view thereof;

FIG. 3 is a fragmentary side elevational view thereof;

FIG. 4 is a fragmentary top plan view thereof;

FIG. 5 is a front perspective view similar to that of FIG. 1, but showing the surface heating unit in extended position;

FIG. 6 is a fragmentary top plan view with the surface heating unit extended; and

FIG. 7 is a fragmentary side elevational view, also with the surface heating unit extended.

The side of the cooking range which is not shown is substantially the same in appearance as the side shown.

The dominant features of my design reside in the portions shown in full lines.

I claim:

The ornamental design for a cooking range, as shown and described.
